ANTIBUMPING DEVICE

George L. Doelling, St. Louis, Mo.

Application October 27, 1941, Serial No. 416,666

3 Claims. (Cl. 23—292)

1

This invention relates to improvements in "anti-bumping" devices used in vaporization processes. More particularly, the invention relates to improvements in "anti-bumping" devices that are designed to maintain a quantity of air or vapor in contact with the liquid contents of a still, evaporator, boiler, or distilling flask during the vaporization process.

It is one object of the present invention to provide an "anti-bumping" device of simple construction that is effective in preventing "bumping" in the distillation, vaporization, or boiling of liquids.

This invention relates to improvements in "anti-bumping" devices similar to the "anti-bumping" devices disclosed in my co-pending applications, Serial No. 334,949, entitled "Anti-bumping" devices, filed May 13, 1940, and issued November 4, 1941, as Patent No. 2,261,235, and Serial No. 401,737, entitled "Anti-bumping" devices, filed July 10, 1941. This invention is a continuation in part of the invention disclosed in applications Serial No. 334,949, issued November 4, 1941, as Patent No. 2,261,235, and Serial No. 401,737.

When "bumping" occurs, there is some superheating of portions of the liquid to be vaporized. The superheating of portions of the liquid reduces efficiency. "Bumping" also causes the "entrainment" of droplets of liquid by the vapor, that foul the distillate. Preventing "entrainment" necessitates the provision of additional volume in the vaporization apparatus that ordinarily is not needed. It can be seen, therefore, that "bumping" reduces the efficiency of vaporization apparatus. By obviating "bumping" with the devices and methods described herein, it is possible to promote smooth, even vaporization of liquid and thereby increase the efficiency of the vaporization process.

The phenomenon of "bumping" in vaporization processes, is particularly noticeable upon restarting, after the distillation has been interrupted for some reason. During the vaporization process, most of the air that is trapped in an "anti-bumping" device will gradually be displaced by vapor of the liquid to be vaporized. As long as the heating continues, the vapor in the device will contact the liquid and foster the smooth, even vaporization of the liquid. When, however, the vaporization process is temporarily suspended to make a cut, or for the addition of liquid to be vaporized, or for any other reason, the contents cool somewhat. This cooling causes most or all of the vapor in the "anti-bumping" device to

2

condense into liquid. On re-heating, there may be insufficient air or uncondensed vapor in the device to foster quiet vaporization of the liquid, and "bumping" may ensue. Especially is this true where the vaporization is done under reduced pressure. Where the vaporization is done under reduced pressure, a good portion of the air initially held by the "anti-bumping" device is drawn out by the vacuum. The air that remains in the device is gradually replaced by vapor, until very little air remains in the "anti-bumping" device. If the still is opened to permit insertion of additional liquid to be vaporized, the pressure will increase and the contents will cool. In such a case, practically all of the vapor in the "anti-bumping" device will condense. On re-heating, the liquid will quite probably "bump."

The various "anti-bumping" devices disclosed in my co-pending applications, Serial No. 334,949, issued November 4, 1941, as Patent No. 2,261,235, and Serial No. 401,737, avoided "bumping" after a heating and cooling cycle by various means. Some of the devices had a normally closed connection to the atmosphere outside of the vaporization apparatus, that could be opened manually to charge the device. Others were arranged to catch and hold the vapor evolved by "bumping" of the liquid, and thus be charged. The improved "anti-bumping" devices contemplated by the present invention have a new and different means to foster smooth vaporization after a heating and cooling cycle. This means consists of a reservoir for air. This reservoir holds a supply of gas, air, or vapor that is normally isolated from the main portion of the "anti-bumping" device. This supply of gas, air, or vapor in the reservoir may contract during the cooling cycle, but it will expand during the re-heating cycle and will combine with the evolution of vapor from the liquid in the reservoir to charge the "anti-bumping" device. This is quite useful because it automatically avoids all "bumping" after a heating and cooling cycle. It is, therefore, an object of the present invention to provide an "anti-bumping" device having a reservoir for air.

"Anti-bumping" devices can be used to advantage in large vaporization apparatus. Where this is the case, it is desirable to provide a plurality of chambers to foster smooth vaporization. Some of the "anti-bumping" devices disclosed in my co-pending applications had a plurality of chambers. These "anti-bumping" devices are quite useful, but their utility can be increased even more by the provision of a reservoir for air. It is, therefore, an object of the present inven-

tion to provide an "anti-bumping" device having a plurality of interconnected chambers and a reservoir for air.

Other objects and advantages of the invention will appear from the drawings and accompanying description.

In the drawings and accompanying description, several preferred embodiments of the invention have been shown and described, but it is to be understood that the drawings and accompanying description do not limit the invention, and the invention will be defined by the appended claims.

In the drawings,

Fig. 1 is a partial cross-sectional view of a flask that shows a side elevational view of an "anti-bumping" device positioned therein.

Fig. 2 is a partial cross-sectional view of a flask that shows a side elevational view of another form of "anti-bumping" device positioned therein.

Fig. 3 is a front elevational view of an "anti-bumping" device.

Fig. 4 is a partial cross-sectional view of a flask that shows a side elevational view of another form of "anti-bumping" device therein.

Fig. 5 is a perspective view of an "anti-bumping" device.

Fig. 6 is a perspective view of another "anti-bumping" device, and

Fig. 7 is a front elevational view of the "anti-bumping" device, shown in Fig. 6.

Referring to the drawings in detail, in Fig. 1, a distilling flask is denoted by the numeral 10. Positioned inside of the flask 10 and securely attached thereto is an "anti-bumping" device 12. The "anti-bumping" device 12 consists of a hollow tube that is bent to form a chamber 14 and a reservoir 16. The chamber 14 has a closed upper portion, an opening 18, and an opening 20. The opening 18 is positioned a distance below the closed upper portion of the chamber 14, and the opening 20 is positioned below opening 18, but in the chamber portion of the tube. When liquid is poured into the flask 10, it will enter the chamber 14 and the reservoir 16 through openings 18 and 20. The reservoir is open only at the bottom, so the level of the liquid in the reservoir will not rise much above the bend in the tube. The level of the liquid in the chamber 14 will rise to the level of opening 18. The liquid will, therefore, trap air in the reservoir 16 and the chamber 14, and will normally isolate the two from each other. Where desired, the "anti-bumping" device may be charged with a gas instead of air. This gas may be one of a number of gases that are in the gaseous state throughout the temperature range of the vaporization process and preferably are not freely soluble in the liquid to be vaporized. For the sake of convenience, the word "air" will be intended to comprehend such a gas as well as air wherever the word "air" appears in the specification and claims. The reservoir will normally be isolated from the chamber by the liquid to be vaporized, and will function to maintain the air in the reservoir separate from the vaporization occurring in the chamber. When the flask is heated, the chamber 14 will operate to promote even vaporization in the manner of the "anti-bumping" devices disclosed in my co-pending applications Serial No. 334,949, issued November 4, 1941, as Patent No. 2,261,235, and Serial No. 401,737. The liquid in the chamber 14 will contact the air in the upper portion of the chamber and will vaporize quite readily. The vapor that

is evolved from the liquid will issue from the chamber through opening 18. The ever-diminishing supply of liquid in the chamber will be continually replenished by liquid entering through the lower opening 20. This liquid will be vaporized without any "bumping." If the heating operation is temporarily suspended, a cooling of the contents of the flask will ensue. This cooling will result in a condensation of the vapor in the chamber 14. Where the heating cycle has been prolonged for some time, the air initially entrapped in the chamber 14 will have been displaced practically completely by vapor of the liquid to be vaporized. In such a case, the chamber will be practically completely filled with liquid during the cooling cycle. In a subsequent re-heating cycle, the chamber 14 must be charged with air or vapor, or the liquid in the flask 10 will "bump." The device in Fig. 1 is charged by air or vapor from the reservoir 16. On re-heating, the air or vapor held in the reservoir will expand and will also foster the vaporization of the liquid in the reservoir. The combined action of vaporization and expansion will quickly fill the reservoir with air and vapor, and will soon cause vapor to move around bend 19 into chamber 14. This will recharge the device. The device is thus recharged after a heating and cooling cycle without any "bumping" whatever.

An "anti-bumping" device of slightly different design is shown in Fig. 2. This device consists of two hollow chambers 22 and 24, and a reservoir 26. Each of the chambers 22 and 24 has an opening 28 in the side thereof and an opening 30 in the bottom thereof. The opening 28 in the side of the chamber is an outlet for vapor and the opening 30 in the bottom of the chamber is an inlet for liquid. The reservoir 26 is connected to the chamber 24 by a bend 32 and it has a closed upper end. This bend preferably should not be above the level of the outlets 28 for vapor. If it were above the level of the outlets 28, the reservoir and the chamber would not normally be isolated from each other by the liquid in the chamber. The device is positioned in and securely attached to the flask 11. When liquid is poured into the flask 11, it enters the chambers 22 and 24 through openings 28 and 30. The liquid will also enter the bend 32 and will normally isolate the reservoir 26 from the chamber 24. Air will be entrapped in the upper portions of chambers 22 and 24, and will foster the smooth vaporization of the liquid. During distillation, the air in the chambers will gradually be displaced by vapor until the chambers have practically no air in them. If the contents of the vaporization apparatus are then cooled, the vapor in the chambers will condense into liquid. On re-heating, the chambers must be recharged, or "bumping" will ensue. The chambers are recharged automatically by the air or vapor from the reservoir 26. As the liquid gets warm, the air in the reservoir will expand and will also foster vaporization of the liquid in the reservoir. The combined action of expansion and vaporization will fill the reservoir to overflowing and vapor will pass around the bend 32 into the chamber 24 and charge it. The evolution of vapor in chamber 24 will then cause bubbles of vapor to pass into chamber 22 through connecting member 23. This member is preferably not above the level of the vapor outlets 28. The reservoir 26, therefore, automatically recharges the "anti-bumping" de-

vice and prevents any "bumping" of the contents of the vaporization apparatus. This type of "anti-bumping" device is quite useful because it fosters smooth vaporization at a number of points in the vaporization apparatus and materially increases the rate of vaporization.

Fig. 3 shows an "anti-bumping" device that may be used in various forms of vaporization apparatus. This device has an upstanding hollow portion 34 that serves as a reservoir and as an extension. The extension 34 engages an upper portion of the vaporization apparatus and maintains the device in the operative position and has a closed upper portion. It also operates as a reservoir for air or vapor. The "anti-bumping" device itself consists of two interconnected chambers 36 and 38. The chamber 36 is located above chamber 38, but is connected to it. The chamber 36 has at least one opening 40 in addition to the opening 42 where it is connected to chamber 38. Chamber 38 has at least two openings 44 and 46. When this device is placed in a vaporization apparatus and liquid is poured into the apparatus, liquid will fill the portions of chamber 36 below the opening 40, will fill the portion of the chamber 38 below the opening 44, and will fill the bend 48. The rest of the device will be filled with air that will foster even vaporization of the liquid. The utility of this particular device is that vaporization can take place simultaneously at different levels in the liquid. As the liquid vaporizes and its level in the still falls, evolution of vapor will continue from openings 40 and 44 until the liquid level is below opening 40. Vapor will continue to issue from opening 44 until the liquid level is below the opening 44. After this, vaporization will occur from the opening 46 until the liquid level falls to this point. At this time, the ratio of the surface of the liquid to the volume of the liquid is so large that the problem of the "bumping" is no longer of any concern. If the vaporization process is suspended while there is still a sizeable quantity of liquid in the vaporization apparatus, the contents will cool down and the vapor in chambers 36 and 38 will condense into liquid. On re-heating, the device will be recharged automatically by air and vapor issuing from the reservoir 34. Air or vapor from the reservoir will be caught in chamber 38. This air or vapor will foster vaporization in chamber 38 until the upper portion of the chamber is filled with vapor. Vapor will then bubble out of holes 42 and 44. The vapor passing through the opening 42 will be caught in chamber 36 and will charge the chamber. In this way, the device will be recharged without any "bumping" of the liquid.

Fig. 4 shows an "anti-bumping" device similar to the device shown in Fig. 1. This device has a chamber 49 similar to chamber 14 and a reservoir 50 similar to reservoir 16. The device is different from the device shown in Fig. 1, in that this device is not permanently attached to the vaporization apparatus and may be removed. The operation of this device is substantially identical with the operation of the device shown in Fig. 1.

Fig. 5 shows another form of "anti-bumping" device. This form of device consists of a reservoir 52 and a chamber 54. The reservoir is formed from a hollow tube with a closed upper end and extends into the chamber 54. The chamber 54 has an open bottom and has notches 56 in its lower edges that function as outlets for vapor. The bottom of reservoir 52 has a notch 58 that is preferably not above the level of the

notches 56. The device may be made so that it can stand by itself or it may be made to lean against an upper portion of the vaporization apparatus. When the device is placed in vaporization apparatus containing liquid, the liquid will enter the bottom of the chamber and the bottom of the reservoir. Air will be entrapped in the upper portions of the reservoir and the chamber. The chamber and the reservoir will normally be isolated from each other by the liquid in the chamber. After a heating and cooling cycle, the vapor in the chamber will practically all have condensed into liquid. The device is automatically recharged by re-heating the liquid, since the air and vapor in the reservoir will completely fill the reservoir and will cause bubbling at the bottom of the reservoir. This bubbling will charge the chamber. This device is particularly useful because it maintains vapor in contact with the liquid near the source of heat.

Figs. 6 and 7 shows another form of "anti-bumping" device. This device comprises two interconnected chambers 60 and 62 and a reservoir 64 connected to chamber 62. The chamber 62 has an open bottom and notches 66 in the edges near the bottom of the chamber for outlet of vapor. Chamber 60 has an opening 68 and an opening 70 where it communicates with chamber 62. The opening 70 is preferably not above notches 66. Reservoir 64 has a closed upper portion and is connected to chamber 62 by an opening 72 that is preferably not above notches 66. The reservoir 64 is ordinarily isolated from chamber 62 by the liquid in the bottom of the chamber 62. The recharging of the device is substantially the same as the recharging of the device in Fig. 3. The devices provided by the invention effectively and automatically prevent "bumping" during heating, cooling, and re-heating cycles.

The drawing has shown the devices mounted in distilling flasks, but this was done only for the sake of clarity and convenience. These devices can be used in any kind of vaporization apparatus. The devices may be made so they are self-supporting or they may be used in vaporization apparatus, provided with means to hold the devices in the operating position.

The anti-bumping devices of this invention comprise a chamber and a reservoir for air. The chamber may be made in any suitable shape but it must have a closed upper portion, an inlet for liquid, and an outlet for vapor. In some cases, a single opening can serve the dual purpose of inlet for liquid and outlet for vapor, and the chamber will then have only one opening. The reservoir is preferably connected to the chamber at a point not higher than the outlet for vapor. Furthermore, at least a part of the reservoir is preferably positioned higher than the bottom of the chamber so the reservoir will trap air therein.

"Bumping" is objectionable for many reasons. Many of these are detailed in my co-pending applications, Serial Numbers 334,949, issued November 4, 1941, as Patent No. 2,261,235 and 401,737. Not the least objection to "bumping" is the loss of efficiency it causes. I have made tests with the "anti-bumping" devices I have invented, and find that the use of these devices increases the rate of vaporization. This is the case where the device is used in glass, metal lined with glass, metal, or other vaporization apparatus. In making the tests, every precaution was taken to avoid errors. Two stills were placed in the same hot-water bath and their receivers were both connected to the same vacuum line. A stirrer was used to secure

an even temperature throughout the water in the bath. One of the stills was equipped with the "anti-bumping" device shown in Fig. 3, while the other had no "anti-bumping" device. To obviate errors, the "anti-bumping" device was taken from the one still and placed in the other and the test repeated.

In one such series of tests, two 500 cc. copper flasks were each charged with 300 cc. of distilled water. A constant bath temperature was maintained and a constant vacuum was maintained. A total of eight distillations (four pairs) were run for forty minutes each. The combined results of the runs show that four runs with the "anti-bumping" device vaporized 761.1 grams of water, while four parallel runs without an "anti-bumping" device vaporized only 465.0 grams of water. By use of the "anti-bumping" device, 63.7% more water was vaporized in the same length of time.

Similar tests were also run with glass distilling flasks. These tests showed that the use of an "anti-bumping" device can increase the amount of vaporization by 100 per cent or more. These tests clearly show that it is possible to increase the efficiency of vaporization processes tremendously by the use of "anti-bumping" devices.

Whereas the drawings and accompanying description have shown and described preferred embodiments of the invention, it is obvious to those skilled in the art that various changes in form can be made without affecting the scope of the invention.

What I claim is:

1. In combination, a vaporizer and an anti-bumping device comprising an integral structure containing more than two chambers, within the vaporizer and in close proximity to the heating surface thereof, one chamber being sealed and extending above the others and connecting therewith by a discharge passage, said first chamber being without opening above the point of discharge, said other chambers being open at the bottoms thereof and each having a discharge opening thereabove but at sufficient distance be-

low the top of the chambers to give a closed space above said discharge openings.

2. In combination, a vaporization apparatus and an anti-bumping device, said anti-bumping device comprising an integral structure containing more than two chambers, one chamber being sealed and extending above the others and connecting therewith by a discharge passage, said first chamber being without opening except through the discharge passage, said other chambers each having an opening in proximity to the bottom thereof and a discharge opening thereabove but at a sufficient distance below the top of such chamber to give a closed space above said discharge opening, said anti-bumping device being positioned in close proximity to the bottom of said vaporization apparatus so that it will be normally surrounded by and substantially immersed in the liquid being vaporized and will be near the heating surface of said vaporization apparatus.

3. In combination, a vaporization apparatus and a removable anti-bumping device positioned within and resting on the bottom of the said vaporization apparatus so that it will be normally surrounded by and substantially immersed in the liquid being vaporized and will be near the heating surface of the said vaporization apparatus, said anti-bumping device comprising an integral structure containing more than two chambers, one chamber being integrally sealed and extending above the others and connecting therewith by a discharge passage, said first chamber being without opening except through the discharge passage, said other chambers, each having an opening in proximity to the bottom thereof and a discharge opening thereabove but at a sufficient distance below the top of such chamber to give a closed space above said discharge opening, the upper part of said anti-bumping device being adapted to engage a portion of the vaporization apparatus and thereby maintain the said device in the operating position.

GEORGE L. DOELLING.
